FEEDING AND PAY-OFF DEVICE FOR
FILAMENTARY MATERIAL

Frank W. Clarke, Boca Raton, Fla., and Walter J. Koyder,
Meadville, Pa., assignors to Talon, Inc., a corporation
of Pennsylvania

Filed Oct. 16, 1963, Ser. No. 316,605
10 Claims. (Cl. 226—190)

This invention relates broadly to the manufacture of slide fastener stringers of the type having a pre-formed interlocking fastener filament, such as a coiled or spirally-arranged filament woven into or otherwise secured to the edge of a tape, and more particularly, to an improved device for feeding the pre-formed filament from a source of supply, particularly, to a loom or other apparatus in which the filament is adapted to be woven to or otherwise attached to the edge of the tape.

The device of the present invention will be described and illustrated with reference to the weaving into the edge of a tape a continuous pre-formed coiled filament consisting of a series of interconnected convolutions of the type shown and described in the U.S. patent to Nicholas Wahl, No. 2,300,442, dated November 3, 1942. Such a pre-formed filament is made usually of nylon, perlon or of some other suitable plastic filamentary material. While the device of the present invention is shown in connection with a feeding of pre-formed coiled filament, it will be understood that it may be used for feeding any other type of filamentary material.

As is generally known to those skilled in the art, such pre-formed coiled fastener filament is sleazy, stretchable, easily subject to distortion and, consequently, has to be delicately handled in the manufacture of such slide fastener stringers.

While various devices have been heretofore suggested and used for feeding such pre-formed filament from a source of supply to its point of use, they have been entirely unsatisfactory and an unacceptable product resulted. This was due primarily to the stretching of the filament as it passes from the source of supply to the loom thereby resulting in distortion of the convolutions of the filament. It is to a device for controlling the feeding of the filament from the source of supply to its point of use in manufacture that the present invention relates.

Accordingly, it is the general object of the present invention to provide a new and novel means or device for efficiently and for effectively feeding and paying-off filamentary material, such as pre-formed coiled fastener filament, from the source of supply to its point of use.

It is another object of the invention to provide an improved feeding and paying-off device for filamentary material which is simple and inexpensive in its construction and use, and which may be conveniently incorporated with a loom or other apparatus with which it is to be used.

It is a further object of this invention to provide an improved device for feeding and paying-off filamentary material from a source of supply, the actuation of which is responsive to the tension to which the filamentary material is subjected as it passes to its point of use.

Various other objects and advantages of this invention will be more apparent in the course of the following specification, and will be particularly pointed out in the appended claims.

In the accompanying drawings, there is shown for the purpose of illustration, an embodiment which the invention may assume in practice.

In these drawings:

FIG. 1 is a front elevational view of the improved

2

feeding device in accordance with the present invention showing a pair of the devices incorporated with a loom,

FIG. 2 is a side elevational view thereof,

FIG. 3 is a plan view of the one side of the same showing the feeding device positioned to one side of the path of the warp threads into and through a needle loom,

FIG. 4 is an enlarged plan view of the feeding device shown in FIG. 3, partly in section,

FIG. 5 is a sectional view taken on line 5—5 of FIG. 4, and

FIG. 6 is a sectional view taken on line 6—6 of FIG. 5.

The feeding device of the present invention is adapted to be incorporated with a needle loom of the type and construction shown and described in the patent to R. G. Turner, No. 2,902,057, dated September 1, 1959 and in conjunction with the means for weaving a pre-formed slide fastener filament to a tape as shown and described in the co-pending application of James A. Hendley, Serial No. 220,091, filed August 28, 1962, now Patent No. 3,123,103. Accordingly, a detailed description and operation of such a loom and associated mechanism will not be described herein but merely referred to in a general manner as the loom and associated mechanism constitutes no part of the present invention. Reference can be made to the aforesaid patent and patent application for a more detailed description.

The mechanism illustrated in FIG. 1 of the drawings shows a pair of filament feeding devices which it will be understood are adapted to be incorporated with a loom for weaving two slide fastener tapes T simultaneously in side-by-side relation and the feeding of two filaments F to the loom as shown and described in the aforesaid copending patent application. In view of the fact that these feeding devices are identical in construction only one of them will be described in detail.

Now referring more particularly to the drawings, the improved filament feeding device in accordance with the present invention consists of frame 2 which is mounted on the base B of a loom or some other supporting means in the vicinity of which the device of the present invention is to be used. It will be understood that this device is positioned on the loom between the warp creels (not shown) positioned rearwardly of the loom and the source of supply of the filament F, and the take-off mechanism (not shown) positioned forwardly of the loom. The driving means for the various mechanisms is not shown but it will be understood that any suitable means may be provided.

As illustrated in FIG. 1, there is mounted on top of this frame 2, a pair of opposed filament feeding and pay-off devices 3 with one positioned to each side of the path of the warp threads W into and through the loom. With each of these devices 3 there is arranged a horizontal shaft 4 with the outer ends thereof journaled in suitable bearings 5 carried by brackets 6 also mounted on the top of the frame 2 to either side thereof. On the outer end of each of these shafts 4, there is arranged a pulley 7 over and around which there is disposed a belt 8. Each of these belts 8 is arranged around a pulley 9 arranged at each end of an intermediate shaft 10 suitably journaled in the frame 2. There is also arranged on this shaft 10, a pulley 12 over and around which there is disposed a belt 13. This belt 13 is also disposed over and around another pulley 14 secured to a drive shaft 15 also suitably journaled in the frame 2 adjacent the bottom thereof. There is also arranged on this shaft 15 another pulley 16 over and around which there is disposed a drive belt 17. This belt 17 is arranged around another pulley (not shown) arranged on the shaft of a motor (not shown) or another shaft (not shown) associated with the driving mechanism of the loom.

Having described the general arrangement of the improved feeding and pay-off device of the present invention, as illustrated, in combination with a loom with which it is particularly adapted to be used, the construction thereof will now be described more in detail. This device consists of a block-like housing member 20 which is suitably mounted on the top of the frame 2 having a central cylindrical bore 21 into and through which the shaft 4 is axially disposed so as to be arranged circumferentially therearound. There is arranged in and around the inner periphery of the bore 21 of this housing member, a continuous helical groove 23 so as to provide a continuous helical rib 24 therearound, as more clearly shown in FIGS. 4, 5 and 6 of the drawings. The side walls 25 of this continuous rib 24 are arranged preferably at an acute angle to the axis of the shaft and roll so that the opposed side walls of the groove diverge in a direction toward the shaft 4, as more clearly shown in FIG. 6.

There is disposed within the bore 21 of the housing member 20 and secured to the shaft 4 therein, a cylindrical feed roll 26 having the outer periphery thereof spaced from the inner periphery of the bore 21. The periphery of this feed roll is preferably smooth but may be knurled if so desired in order to obtain a more positive feeding action.

In the side wall 27 of this housing member 20 there is provided adjacent the top thereof, a plurality of horizontal feed passageways 28 which are arranged in side-by-side and parallel relation with each communicating with the helical groove 23, 23 opposite and substantially tangential to the periphery of the feed roll 26. In the opposite side wall 29 of this housing member 20 on the opposite side of the feed roll 26, there is arranged a single horizontal delivery passageway 30 which also communicates with the helical groove 23 opposite the periphery of the feed roll 26 and substantially tangential thereto.

In the top of the housing member 20 there is arranged a plurality of elongated parallel slots 32. Each of these slots are arranged directly opposite and in alignment with the helical groove 23 in the housing and communicate therewith for the purpose of manually guiding the filament F around the feed roll and into the helical groove during the initial threading operation.

The improved feeding and pay-off device of the present invention functions in the following manner. It will be assumed that the loom is in readiness for weaving with the warp and weft threads in position therein. The pre-formed filament F is then threaded into one of the feed passageways 28 in the side of the housing, over and around the feed roll 26 into the helical groove 23, and out through the delivery passageway 30 of the housing so as to assume a position in the device, as more clearly shown in FIG. 4 of the drawings. It will be understood that the filament is adapted to be initially guided around the feed roll 26 and into the helical groove 23 by means of the forefinger of the operator through the slots 32. The filament F is then disposed along side of the warps and threads into and through a channel (not shown) in the guide G, as shown in FIG. 3. Guide G is pivotally mounted adjacent the outermost warp in a manner such that oscillatory movement perpendicular to warps W of guide G will permit a laterally reciprocating needle (not shown) to insert a weft thread alternately above and below the entrance of the channel in synchronism with the oscillatory movement of guide G. The exit of the channel is located substantially at the pivotal axis of guide G such that the filament F exits therefrom at a point adjacent to the fell of the tape at which point the filament is woven into the edge of the tape during the weaving operation.

The loom is now set in operation and as the take-up mechanism or delivery roll pulls the warps W into the loom the filament F will likewise be pulled thereinto for weaving. Initially there is a certain amount of slack in

the filament F and when this is taken up between the guide G and the feeding device 3 by the weaving operation, the filament F will become taut and be moved into contact with the periphery of the revolving feed roll 26 at the delivery side of the housing. The filament will then be caused to be fed out through the delivery passageway 30 due to friction and the tautness of the filament at this particular instant. It will be understood that the feed roll 26 is being continuously rotated as a speed substantially faster than the linear speed of the filament and the take-up mechanism of the loom so as not to subject the filament F to excessive tension between the guide G and the feeding device 3. As the filament F is moved out through the delivery passageway 30, the successive convolutions of the filament F disposed around the feed roll 26 will be forced into contact with the periphery of the feed roll and a predetermined length of filament will be pulled or drawn into the device around the feed roll 26 from the source of supply. After a predetermined length has been drawn, the filament will assume the position in the helical groove 23, as shown at A in FIG. 6, out of contact with the periphery of the feed roll and will remain there until the filament between the guide G and the device 3 again becomes taut and is again forced into contact with the periphery of the feed roll, as shown at B in FIG. 6.

Thus, it will be seen that the filament will not be payed-off from the source of supply and fed into the loom by the feed roll 26 until the filament is under tension at the weaving operation and that the filament will normally be out of contact with the periphery of the feed roll and will be payed out thereby only at the proper time responsive to a certain condition. That is to say, the convolutions of the filament disposed around the feed roll 26 will normally assume an expanded position in the helical groove 23 at a spaced distance from the periphery of the feed roll, as shown in FIG. 6.

As a result of the present invention it will be seen that there is provided a new and novel device for paying-off and feeding a filamentary material from a source of supply to a loom for weaving or for some other use whereby the material is not subjected to excessive tension during the feeding thereof thereby eliminating the danger of stretching or otherwise distorting the material.

While we have shown and described an embodiment which our invention may assume in practice, it will be understood that this embodiment is merely for the purpose of illustration and description, and that other forms may be devised within the scope of the invention as defined in the appended claims.

What we claim as our invention is:

1. A device for paying-off and feeding continuous filament from a source of supply to a take-up comprising,
 a cylindrical feed roll rotatably mounted,
 means for rotating said feed roll at a predetermined speed,
 a housing member arranged circumferentially around said feed roll so as to encircle the same having an inner periphery spaced from the outer periphery of said roll,
 means for guiding the filament in the space around said roll between the periphery of said roll and said housing member,
 said filament responsive to the tension to which it is subjected by said take-up for moving between a first position wherein the filament engages the peripheral surface of said feed roll to advance said filament from said supply, and a second position wherein the filament is displaced from engagement with the peripheral surface of said feed roll and moved into engagement with the inner surface of said housing member.

2. The combination as defined in claim 1 wherein the means for guiding the filament in the space around said feed roll consists of a helical groove arranged in the inner periphery of said housing member in which the filament is adapted to be disposed as it passes around said feed roll. 5

3. The combination as defined in claim 1 wherein there is arranged in the top of said housing member a plurality of slots directly opposite and in alignment with helical groove therein for the purpose of threading the filament in and around said feed roll and into the helical groove. 10

4. A device for paying-off and feeding continuous length filament from a source of supply to a take-up comprising,

a cylindrical feed roll rotatably mounted,
means for rotating said feed roll at a predetermined speed,
a housing member arranged circumferentially around said feed roll so as to encircle the same having an inner periphery spaced from the outer periphery of said roll,
a filament feeding passageway arranged in said member,
a filament delivery passageway arranged in said member on the side of said member opposite that of said first passageway,
means for guiding the filament in the space around said roll between the periphery of said roll and said housing member,
said filament responsive to the tension to which it is subjected by said take-up for moving between a first position wherein the filament engages the peripheral surface of said feed roll to advance said filament from said supply, and a second position wherein the filament is displaced from engagement with the peripheral surface of said feed roll and moved into engagement with the inner surface of said housing member. 30

5. The combination as defined in claim 4 wherein the means for guiding the filament in the space around said feed roll consists of a helical groove arranged in the inner periphery of said housing member in which the filament is adapted to be disposed as it passes around said feed roll. 40

6. The combination as defined in claim 4 wherein there is arranged in the top of said housing member a plurality of slots directly opposite and in alignment with helical groove therein for the purpose of threading the filament in and around said feed roll and into the helical groove. 45

7. A device for paying-off and feeding continuous length filament from a source of supply to a take-up comprising,

a cylindrical feed roll rotatably mounted,
means for rotating said feed roll at a predetermined speed,
a housing member arranged circumferentially around said feed roll so as to encircle the same having an inner periphery spaced from the outer periphery of said roll,
said member having a helical groove arranged around the inner periphery thereof,
a filament feeding passageway arranged in said member opposite said helical groove at one side thereof,
a filament delivery passageway arranged in said member opposite said helical groove on the side of said member opposite that of said first passageway, 55

said filament passes into and through the feed passageway, in and around the helical groove and the feed roll and is responsive to the tension to which it is subjected by said take-up for moving between a first position wherein the filament engages the peripheral surface of said feed roll to advance said filament from said supply, and a second position wherein the filament is displaced from engagement with the peripheral surface of said feed roll and moved into engagement with the inner surface of said housing member. 15

8. The combination as defined in claim 7 wherein there is arranged in the top of said housing member a plurality of slots directly opposite and in alignment with helical groove therein for the purpose of threading the filament in and around said feed roll and into the helical groove. 20

9. A device for paying-off and feeding continuous length filament from a source of supply to a take-up comprising,

a cylindrical feed roll rotatably mounted,
means for rotating said feed roll at a predetermined speed,
a housing member arranged circumferentially around said feed roll so as to encircle the same having an inner periphery spaced from the outer periphery of said roll,
said housing member having a helical groove arranged around the inner periphery thereof so as to provide a continuous helical rib therearound with the side walls of said rib being arranged at an acute angle to the axis of said roll,
a filament feeding passageway arranged in said member opposite said helical groove at one side thereof, a filament delivery passageway arranged in said member opposite said helical groove on the side of said member opposite that of said first passageway, said filament passes into and through the feed passageway, in and around the helical groove and the feed roll and is responsive to the tension to which it is subjected by said take-up for moving between a first position wherein the filament engages the peripheral surface of said feed roll to advance said filament from said supply, and a second position wherein the filament is displaced from engagement with the peripheral surface of said feed roll and moved into engagement with the inner surface of said housing member. 30

10. The combination as defined in claim 9 wherein there is arranged in the top of said housing member a plurality of slots in directly opposite and in alignment with helical groove therein for the purpose of threading the filament in and around said feed roll and into the helical groove. 45
